US0D1101931S

(12) **United States Design Patent** (10) **Patent No.:** **US D1,101,931 S**
(45) **Date of Patent:** **** Nov. 11, 2025**

(54) **PHYSIOLOGICAL DATA RECORDER**

(71) Applicant: **DORMOTECH MEDICAL LTD.,**
Kochav Yair (IL)

(72) Inventors: **Abd El-Kader Naser**, Tira (IL);
Shlomo Zucker, Mikhmoret (IL)

(73) Assignee: **DORMOTECH MEDICAL LTD.,**
Kochav Yair (IL)

(**) Term: **15 Years**

(21) Appl. No.: **29/882,850**

(22) Filed: **Jan. 19, 2023**

(51) LOC (15) Cl. **29-02**

(52) U.S. Cl.
USPC **D24/110.1**

(58) **Field of Classification Search**

(57) **CLAIM**

The ornamental design for a physiological data recorder as shown and described.

DESCRIPTION

FIG. 1 is a front perspective view of a physiological data recorder in accordance with the new design;

FIG. 2 is a front view thereof;

FIG. 3 is a rear view thereof;

FIG. 4 is a top view thereof;

FIG. 5 is a bottom view thereof;

FIG. 6 is a right view thereof; and,

FIG. 7 is a left view thereof.

The broken lines depict portions of the physiological data recorder that form no part of the claimed design.

1 Claim, 7 Drawing Sheets
